UNITED STATES PATENT OFFICE.

JAMES R. FOX, OF CHICAGO, ILLINOIS.

AUTOMATIC DELIVERY DEVICE FOR PLATENS OF PRINTING-PRESSES.

SPECIFICATION forming part of Letters Patent No. 742,980, dated November 3, 1903.

Application filed March 16, 1903. Serial No. 147,895. (No model.)

To all whom it may concern:

Be it known that I, JAMES R. FOX, a citizen of the United States, residing at Chicago, in the county of Cook and State of Illinois, have invented certain new and useful Improvements in Automatic Delivery Devices for Platens of Printing-Presses, of which the following is a specification.

My invention relates to certain new and useful improvements in automatic delivery devices for platens of printing-presses, and is especially adapted for use on presses operated by hand-levers.

The object of my improvements is to provide a device which may be attached to the press-platen and which will automatically remove cards, envelops, and the like therefrom during the operation of the press, thus saving the pressman loss of time and permitting the press to be operated much faster than when the printed matter is removed with the hand, as is usually done. I attain these objects by means of the mechanism illustrated in a preferred form in the accompanying drawings, in which—

Figures 1 and 2 are views in side elevation of a printing-press bed and platen having my device attached thereto and in two operative positions. Fig. 3 is a face view or front elevation of the platen, showing one part of my device attached thereto. Fig. 4 is a side view in elevation of the part of my invention shown in Fig. 3, but detached from the platen. Fig. 5 is a top plan view of the part of my invention which is adjustably attached to a portion of the press-frame, and Fig. 6 is a side elevation of same.

Referring to the drawings in detail, A represents the frame, to which the press-bed B is secured in any usual manner, and C the platen, which is bolted to the arms D, which are hinged on the frame R.

The parts thus far enumerated are of the character and arrangement in general use in platens of well-known types and form no part of my invention proper, which is applicable to any platen-press.

E represents a clamp which has jaws e' adapted to receive and be secured to the lower edge of the platen by means of the thumb-screw e^2 , which passes through the upper or rear jaw of the clamp and frictionally

engages or impinges against the lower edge of the rear side of the platen.

H represents a lever which is preferably formed from a single piece of sheet metal and pivotally secured to the said clamp by means of a pivot e^3 , passing through an opening in the lower corner of the clamp and through the ears h' , formed on each side of the lever. 60

K is a tongue or strip of metal adjustably connected to the front part of the lever by means of the overhanging edges of the ears h^2 , formed on the lever below the ears h' and at right angles thereto, as shown in Fig. 4. 65 Said tongue has a flat thin point at its upper end adapted to lie close against the face of the platen and back of the lower edge of a card, envelop, or other matter to be printed, as L. The tongue is slidably held between the ears h^2 , and therefore adapted to be moved up or down on the lever, as desired, the frictional contact being sufficient to hold it in any adjusted position. The rear or outer end of the lever is bent downward, as shown, 70 to form a hook h^3 , which is adapted to engage the upper edge and point of a dog M, pivotally mounted in a standard N, adjustably secured to a portion of the frame R by means of a bolt S, which passes through a slot n' in the standard and through the slot r' in the frame R. By means of these slots and bolt the dog may be adjusted to any desired position relative to the position of the lever, and the latter may also be suitably adjusted 75 by securing the clamp E at different points along the lower edge of the platen.

In use my invention operates thus: When the platen is in the position shown by the full lines in Fig. 1, the hook on the lever is below 90 and engaged by the outer point of the dog. As the platen moves forward toward the type or press-bed the lever H follows and turns the dog backward and upward until it assumes the position indicated by dotted lines 95 in Fig. 1, in which position it releases the dog, which then swings back into its normal position. Then as the platen recedes from the type the hooked end of the lever rests upon the upper adjacent edge of the dog, and as the lever moves back on the dog, which is preferably inclined upward toward its point, the upper end or point of the metal tongue K is moved outwardly from the platen, as 100

shown by dotted lines in Fig. 2, and the point of the tongue being behind the lower edge of the card pushes one end of the latter from contact with the gage-pin c' , whereupon the 5 card (which has its opposite end still resting upon the gage-pin c^2) makes a quarter-turn and drops by gravity endwise into any receptacle which may be provided below the platen.

10 Having thus described my invention, what I claim as new, and desire to secure by Letters Patent, is—

15 1. In combination with the frame and platen of a printing-press, means for delivering the printed matter, such as cards, envelopes and the like, said means comprising an adjustable tongue adapted to lie against the platen and back of the printed matter, a holder for said tongue, means for adjustably 20 attaching the holder to the platen, and means for automatically operating said holder.

2. In combination with the frame and platen of a printing-press, means for delivering the printed matter, said means comprising 25 a vertically-adjustable tongue adapted to lie against the platen and back of the printed matter, a lever having portions adapted to hold said tongue by frictional contact, means for attaching the lever to the platen,

and means for automatically operating said lever.

3. In combination with the frame and platen of a printing-press, means for delivering the printed matter, said means comprising a vertically-adjustable tongue adapted to 35 lie against the platen and back of the printed matter, a lever having portions adapted to hold said tongue, means for attaching the lever to the platen, and adjustable means for automatically operating said lever. 40

4. In combination with the frame and platen of a printing-press, means for delivering the printed matter, said means comprising a slidably-mounted and vertically-adjustable tongue adapted to lie against the platen 45 and back of the printed matter, a clamp adjustably secured to the platen, a lever pivotally mounted on said clamp and supporting said tongue, and a dog adjustably mounted on the frame and adapted to operate said 50 lever upon the movements of the platen.

In testimony whereof I affix my signature in presence of two witnesses.

JAMES R. FOX.
